UNITED STATES PATENT OFFICE.

WILLIAM D. SNYDER, OF CHICAGO, ILLINOIS.

WARDROBE-BEDSTEAD.

SPECIFICATION forming part of Letters Patent No. 474,869, dated May 17, 1892.

Application filed April 3, 1891. Serial No. 387,559. (No model.)

To all whom it may concern:

Be it known that I, WILLIAM D. SNYDER, of Chicago, in the State of Illinois, have invented certain new and useful Improvements 5 in Folding Bedsteads, of which the following is a specification.

My invention relates to folding bedsteads in which a coil-wire or elastic bed-bottom is used in conjunction with the bed-frame and 10 adapted to be drawn taut and slackened by the operation of opening and closing the bed; and the object of my improvement is to simplify and better the connection of such bed-bottom with the head end of the bed-frame 15 for supporting and operating the same in the manner above indicated. This object I have attained in the bedstead constructed as illustrated in the accompanying drawings, in which—

20 Figure 1 is a central section of a closed bedstead of the class mentioned containing my invention. Fig. 2 is a like view of the same open.

In the drawings, A designates the standard, 25 and B the bed-frame. The bed-frame is pivoted to the standard at a in an ordinary way and has automatic foot-legs b. C is the elastic bed-bottom, which is secured at the foot end to a rail c, made fast at each of its ends to the 30 side rails of the bed-frame, and at the head end to a rail c', which is provided with an end piece c², secured to each end of it and adapted to come on the inside of the side rails of the bed-frame. The said side rails are provided 35 on each side of the bed with a pin a', secured by means of a plate a², integral with said pin and attached to said side rails by screws. The pieces c² are provided with a slot c³, by which 40 they are loosely connected with the bed-frame by the engagement of said slots over the pins a'. The ends of the rails c' are provided with a pin e, projecting from said ends and adapted to enter and play in a slot e' in a board or plate E, attached to each side of the standard, 45 the slot being open at one side at the top. When the bed is closed, these pins e drop down to the bottom of said slots e', and when the bed is opened they rise therein until they strike stop e², formed by a short curve at the 50 top of said slots e' and about on a level with

the bed-bottom C when let down to the horizontal. The bed-frame stops in horizontal position before the pieces c² and bed-bottom have passed the center of motion, so that the pull of the bed-bottom will hold rail c' up 55 against stop e² under the weight of the occupant while the bed is open. The pillow-board F is hinged to the rails c' and has its top edge rested against stops f, secured to the side boards of the standard. A counterpoise G is 60 provided for balancing the bed-frame, and springs H are adapted to support the central portion of the bed-bottom.

The connection of the bed-bottom with the head and of the bed-frame by means of the 65 slotted end pieces of rails c', engaging pins a' of the bed-frame, in conjunction with pins e of said rail, engaging slots e' of the standard, operates as follows: When the bed-frame is upright, pins a' are at the outer ends of slots 70 c³, and pins e rest in the bottom of slots e' and support rail c'. During the first part of the letting down the bed, pins a' travel toward the opposite ends of slots c³ without raising rail c'. By this part of the movement the bed- 75 bottom is straightened so as to exert thereafter a pull on said rail, which pull by the further movement raises said rail to the top of slots e' by sliding pins e upward therein. The movement thus far also brings pins a' to 80 the inner ends of slots c³, and pins a' then carry the weight of rail c' and raise pins e against stops e². On closing the bed the pins e enter the slots e' at the point where the pins a' begin to recede in slots c³, and where but for 85 said slots said pins would begin to pull rail c' forward.

What I claim is—

1. In a wardrobe-bedstead, and in combination, the standard, the bed-frame pivoted to 90 the standard, an elastic bed-bottom secured at the foot to a cross-rail c, attached to the bed-frame and at the head to a rail c', pieces c², attached at each end to the rail c' and provided with a slot c³, adapted to engage pins 95 a', secured to the side rails of the bed-frame, pins e, projecting from the ends of said rail c', and plates E, provided with slots e', secured to the sides of the standard, all arranged, as shown, relatively to one another. 100

2. In a folding bed of the class described, the combination, with the bed-frame, of the rail c' , provided with end pieces c^2 , having slots c^3 , engaging over pins on the side rails, 5 and an elastic bed-bottom connected to the bed-frame and to said rail c' , and a stop on the standard adapted to check the motion of the end pieces c^3 for stretching the bed-bottom and holding it in place while the bed is open, substantially as specified.

WILLIAM D. SNYDER.
